(57) **CLAIM**

The ornamental design for a headlight as shown and described.

DESCRIPTION

FIG. 1 is a perspective view of a headlight showing our new design;

FIG. 2 is a front view of the headlight;

FIG. 3 is a rear view of the headlight;

FIG. 4 is a plan view of the headlight;

FIG. 5 is a bottom view of the headlight;

FIG. 6 is a right view of the headlight; and,

FIG. 7 is a left view of the headlight.

The dot-dash broken lines in the figures and the areas within the dot-dash broken lines show portions of the headlight and environment that form no part of the claimed design.

1 Claim, 7 Drawing Sheets
